UNITED STATES PATENT OFFICE.

CHRISTOPHER STRAUB, OF EAST ELMHURST, NEW YORK, ASSIGNOR, BY MESNE ASSIGNMENTS, TO ASTORIA IMPORTING AND MANUFACTURING CO. INC.

COMBINED MACHINE.

Application filed August 4, 1925. Serial No. 48,932.

Veneer is frequently made from what is generally known as the stumps of walnut trees because of the particularly beautiful grain which may be obtained by the use of 5 that part of the tree. For the purpose of cutting the veneer from the stump it is generally cut into sections including the median line or axis of the tree and such sections which are termed flitches may include 10 one-half the circumference of the tree or one quarter thereof and are termed, respectively, half butt flitches and quarter butt flitches. A butt flitch is then placed upon a stay log rotatable about its axis and the 15 sheets of veneer are stripped from the flitch by relatively stationary knives against which the flitch is moved by the rotation of the stay log. As the stump decreases considerably in its diameter within a comparatively 20 short distance and as the elements of the circumference of the flitch must rotate in a cylindrical plane parallel to or including the knife edge, it is necessary to remove a section or slab of the flitch from what was 25 the center of the stump in order that it may lie upon the stay log with the elements of the circumferential surface of the flitch parallel to the axis about which the stay log rotates. Heretofore, the removal of the wedge shaped 30 slab has been effected by hand by means of an adze or the like which has proven a laborious and time consuming operation with consequent increase in manufacturing costs. With the half butt flitch a groove is cut 35 down what was the center of the stump which decreases in depth from the end of greatest diameter to the end of least diameter of the stump. In quarter butt flitches which are segmental in cross section a wedge 40 shaped slab including the apex thereof is removed. These operations have heretofore been performed manually. It is also frequently desirable to plane the surface of a log preparatory to the removal of the veneer 45 therefrom. The present invention has for its object to provide a machine which shall be capable of performing the various operations enumerated above automatically and thus do away with the time consuming manual operation. Accordingly, what is termed 50 a variety planer has been devised which is capable of performing the various desired operations more or less automatically. More particularly, a reciprocating carrier upon

which the flitch may be conveniently placed 55 with the elements of its circumferential surface substantially parallel to the plane of travel thereof is adapted to bring a flitch in contact with a rotary knife or knives whereby, with successive cuts, a groove may be 60 formed as pointed out hereinbefore. Provision is also made for removing a slab from a quarter butt flitch through the instrumentality of an independent reciprocating carriage, the rotary saw by which such cut is 65 made being carried upon a shaft which may also serve to carry the planing means or if desired, a knife head also capable of cutting the groove. These and other objects of the invention will now be described in greater 70 particularity in connection with the accompanying drawings illustrating preferred embodiments of the invention, wherein:

Figure 1 is a view in side elevation showing 75 the machine according to the present invention and a flitch in position on the carrier preparatory to cutting a slot therein, taken in the plane indicated by the line 1—1 in Figure 2, that portion of the machine indicated to the right of line 1—1 in Figure 2 being removed in the interest of clearness.

Figure 2 is a view in end elevation showing 80 the machine looking from the left in Figure 1.

Figure 3 is a plan view of the machine.

Figure 4 is a fragmentary view showing 85 automatic setting devices to control the depth of each cut in cutting the groove.

Figure 5 is a fragmentary detailed view 90 taken in the plane indicated by the line 5—5 in Figure 1 and looking in the direction of the arrows.

Figure 6 is a view partly in section and 95 partly in elevation of a modified form of cutter head which is carried with a transversely extending shaft.

Figure 7 is a view in end elevation showing 100 a modified reciprocating carriage for use in conjunction with the circular saw.

Figure 8 is a view showing the carrier in side elevation looking from the right in Figure 7.

Figure 9 is a view in plan showing a modified construction for actuating the 105 screws by which the knife carrier is raised and lowered.

Referring to Figure 1 a half round flitch a within which a groove is to be cut as at a'

and which has already been cut as indicated at a^2 is shown as rigidly secured upon a reciprocating carriage b between a stationary chuck b' and an adjustable chuck b^2 . The carriage is mounted upon the wheels b^3 whereby the carriage is enabled to reciprocate on the tracks c which are supported upon a firm foundation d . The carriage may be reciprocated in any convenient way. 10 In the illustrated embodiment a rack b^5 is illustrated as mounted beneath the frame of the carriage upon either side thereof and is in mesh with pinions b^6 carried upon a transversely extending shaft b^7 journaled in 15 the rails c and adapted to be rotated in either direction by any convenient actuating means. Obviously, other devices may be adapted for reciprocating the carriage as, for instance, a worm gear and shaft actuated by a reversible 20 electric motor or the like. Upon either side of the rails are disposed vertical ways or guides e, e' , connected at their top by a cross head e' . A carrier f is adapted to be reciprocated along the ways e by means of threaded rods g, g , journaled at their lower ends adjacent the tracks c and near their upper end in the cross head e' . Above the cross frame member e' , each screw is provided with a bevel pinion g' constantly in mesh 25 with bevel pinions g^2, g^3 , rotatably carried with a transverse shaft g^4 and adapted to be clutched to rotate with said shaft by means of suitable clutching devices g^5 actuated in any convenient manner as by means 30 of the rods g^6 adapted to actuate the respective clutches simultaneously. During the making of the cut the bevel pinions g^2, g^3 are, of course, unclutched and it may be found 35 advantageous in some situations to guard 40 against any desired slight rotation of the threaded rods g which would tend to alter the elevation of the cutter head. A modified construction to accomplish this purpose is illustrated in Figure 9 wherein the pulley G^8 is shown as mounted upon the shaft G^4 upon which are loosely mounted the bevel pinions G^2 and G^3 but the shaft G^4 is cut off adjacent the bevel pinion G^2 . Pinions G^2, G^3 are adapted to be selectively clutched to the 45 shaft G^4 by means of the clutch G^5 . The bevel gear G' at the left of Figures 2 and 9 is adapted to be driven from the bevel gear G' at the right through an independent drive. To this end a shaft p vertically disposed with respect to the shaft G^4 is supported as by a bracket from the cross member e' and carries at its ends bevel pinions p', p^2 . The bevel pinion p' meshes with the gear G' and the bevel pinions p^2 meshes with a pinion q carried upon a transversely extending shaft q' extending substantially parallel to the shaft G^4 . Upon the opposite end of shaft q' there is carried a bevel pinion q^2 meshing with a bevel pinion r carried upon 50 a shaft r' parallel to the shaft p which has

at its opposite end a bevel pinion r^2 meshing with the bevel gear G' . Thus by means of this, what may be termed, indirect drive, the rotation of the screws g, g' in unison is assured. 70

Carried with the carrier f is a cutter by which the groove a' is cut. This cutter may take the form of blades h carried in a head h' mounted upon the end of a vertically disposed shaft h^2 journaled in a bearing h^3 carried with the carrier f and also journaled in the cross frame member e' . Within an aperture e^2 in the cross head e' there is disposed a pulley h^4 adapted to be driven as by the belt h^5 , and to rotate the shaft h^2 . Since 75 the cutting head h' is lowered after each cut provision must be made for reciprocating the shaft while from practical considerations the belt driven pulley should remain relatively stationary. To this end the shaft h^2 is relatively movable with respect to the pulley h^4 and a driving connection is effected by means of a key h^6 . 80

It will, of course, be obvious that the complete groove need not be formed in the flitch 90 in one cut but that successive cuts of relatively shallow depth may be made. Automatic devices are indicated for lowering the cutter head after each cut dependent upon the reciprocation of the carriage. To this end a

pinion i is illustrated as carried upon the shaft g^4 and is in mesh with a pinion i' carried with a stub shaft i^2 journaled in the cross head e' adjacent the shaft g^4 . A ratchet i^3 is adapted to rotate with pinion i' . A clutch i^4 is also illustrated whereby the ratchet and shaft i^3 may be rotated together in one direction while the shaft will rotate independently of the ratchet in the opposite direction. Rotation of the ratchet is effected by a lever j pivoted adjacent the device and carrying a pawl j' on one arm of the lever which is yieldingly held as by the spring j^2 in engagement with the teeth of the ratchet. The other arm of the lever j is connected as by a link j^3 with the arm of a bell 100 crank j^4 , the other arm j^5 of which is adapted to be engaged by a pin b^4 carried with the carriage b . Suitable yielding devices j^6 are provided which will constantly tend to move the arm j^3 against the action of the pin b^4 whereby the constant tendency of the actuating devices is such as to normally retain the ratchet and dog j' out of engagement. A 105

dog or ratchet j^7 is also illustrated as provided to prevent the rotation of the ratchet in one direction upon disengagement of the actuating devices. 110

The operation of the actuating devices is as follows: After the carriage has traveled toward the right in Figure 1 and the rotating knives h have made a cut in the flitch a the carriage is returned to the position shown at the left in Figure 1 at which time the pin is brought in contact with the 115

bell crank lever j^4 thereby causing the link j^3 to be drawn downwardly and the lever j to cause the rotation in a counterclockwise direction (Figure 4) through a predetermined arc. Such rotation of the ratchet i^3 causes a similar rotation of the pinion i' which in turn causes a rotation of the shaft g^4 . Rotation of the shaft g^4 in turn causes the rotation of the screws g through either the bevel gears g^2 or g^3 . Dependent upon which gear is in mesh with the bevel g' the cross head f will be raised or lowered through a predetermined degree and this in turn will lower the cutter head preparatory to making the next cut.

Due to the variations in the depth of the cut desired as will be obvious from an inspection of the illustration of the flitch in Figure 1 it may be found advantageous in some instances to effect the lowering of the cutter head manually rather than automatically. To this end a pulley g^8 may be carried on the end of the shaft g^4 which is adapted to be driven constantly in one direction by the belt g^9 . When the shaft is rotated by the pulley g^8 the raising or lowering of the carrier f may be effected by clutching the appropriate bevel gear g^2 or g^3 to the shaft.

The arrangement illustrated may also be found advantageous in the performance of other necessary operations. For instance, timbers may be readily planed by taking advantage of the construction just described, together with additional auxiliary parts. Between the rails there may be journaled a plurality of rollers k and a roll l may also be carried with the carrier and adapted to be normally pressed downwardly as by the spring l' . Immediately beneath the roll between the tracks c there may be disposed a knife carrier m carried upon a shaft m' journaled in bearings m^2 carried with the base d and carrying at one end a pulley m^3 whereby the shaft may be rotated. Knives may be inserted in the slots m^4 in the knife carrier m and upon removal of the cutter head h' , the carrier f may then be lowered until the roll l yieldingly engages a stick of timber carried upon the rollers k . The timber may then be moved forwardly over the rolls in any convenient manner to be engaged by the planing devices carried with the head m .

It is frequently found necessary to cut off a slab from the flitch before the operation of cutting the groove is commenced and in quarter flitches a wedge-shaped slab is all that is necessary to be removed. To facilitate this operation the end of the shaft m' may carry a circular saw m^5 and a carriage n , is shown as reciprocable adjacent the circular saw along tracks n' by means of the racks n^2 and pinions n^3 rotatable in any convenient manner. Obviously other

means for reciprocating this carriage may be adopted. A stay log n^4 may be mounted upon the carriage n and may be adapted to retain a flitch by means of the dogs n^5 and the stay log n^4 may be reciprocated toward and away from the saw by manually operable devices indicated in general at n^6 .

A modified form of carriage adapted to travel upon the tracks n' is illustrated in Figures 7 and 8. This carriage is formed of longitudinally extending channels s supported upon the rails n' by the wheels s' . Supported upon the channels s are pairs of transversely extending channels s^2 and supported on the respective pairs of channels are ways s^3 . Journaled in the channels is a shaft t adapted to be rotated by ratchet mechanism t' and carrying between the channels s^2 pinions t^2 , t^2 . These pinions may be slidable with respect to the shaft t but rotated therewith by means of the feathers t^2 . Mounted upon the ways s^3 are standards u having racks u' adapted to mesh with the pinions t^2 . Thus upon rotation of the shaft t by means of the ratchet mechanism t' the standards u may be reciprocated in unison along the ways s^3 and carried upon adjacent faces of the standards are dogs u^2 , u^3 one of which may be stationary and the other adjustable. Occasion may arise, particularly in connection with the use of quarter flitches for varying the relative position of the standards with respect to one another in order that a wedge-shaped slab may be cut from the flitch. To this end provision is made for such movement. This is accomplished by disengaging either or both the pinions t^2 from the racks u' by sliding the pinions along the feathers t^3 out of engagement with the racks and then moving the standards with respect to one another until the desired relation is attained whereafter the pinions t^2 may be again engaged with the racks u' .

Modified devices for cutting a groove in the stay log are indicated in Figures 1 and 6. These devices take the form of a cutter head o adapted to be carried with the knife carrier m and held in position by wedges o^2 secured in position by split nuts o^2 which are adapted to mesh with the threads m^6 , m^6 . On assembly, of course, the head o is slipped on over the carrier m to the desired position, wedges set in the slots m^4 are forced inwardly against the head until absolute rigidity is obtained by the nuts o^2 whereafter the nuts are clamped in position by means of bolts o^3 . The cutter head carries knives o^4 suitably spaced on the circumference thereof. Of course, a recess of sufficient depth for the reception of the head o is provided in the base d and the carriage b is similarly provided with a recess centrally thereof whereby clearance for the head is afforded. With this modification, obviously, the flitch is disposed

110
115
120
125
130

in the dogs b' , b^2 , in a reversed manner so that the groove is cut in the lowermost part of the piece of wood.

It will be thus seen that a machine is provided which is self-contained and capable of performing a plurality of functions in and about a veneer cutting plant. No limitation is intended in the particular form taken by the coacting elements illustrated or hereinbefore described except as indicated in the accompanying claims.

What I claim is:

1. In combination, parallel rails, vertical ways, a carrier movable over the ways, vertical worm shafts by which the carrier is moved, bevel pinions carried on the ends of the worm shafts, respectively, means to selectively engage the pinions, a carriage movable over the rails, a transverse shaft, operative connections between the transverse shaft and the worm shafts, a ratchet carried with the end of the transverse shaft, and means to rotate the ratchet dependent upon the reciprocation of the carriage.
2. In a device of the character described, in combination, a carriage, a rotatable shaft, a plurality of pinions carried with the shaft, means to rotate the shaft, ways carried with the carriage, standards reciprocable on the ways, racks carried with the standards, and means to mesh said pinions with the standards when desired.
3. In a wood cutting machine having a bed, rails carried upon the bed, rollers carried transversely with said rails, vertical ways carried upon the bed, a carrier slidable vertically upon said ways, a rotary cutter mounted with said carrier, manually operable means to adjust the vertical distance between the carrier and the bed, means to rotate the cutter, a movable carriage mounted upon the said rollers, means to retain the work upon said carriage, means to

alternately feed and withdraw the work with respect to the cutter, means operatively associated with said carriage to automatically lower the cutter upon each successive withdrawal of the carriage in preparation for the next cut.

4. In a wood cutting machine having a bed, rails carried upon the bed, vertical ways carried upon the bed, a carrier slidable vertically upon said ways, a rotatory cutter mounted with said carrier, manually operable means to adjust the vertical distance between the carrier and the bed, means to rotate the cutter, a movable carriage, means to retain the work upon said carriage, means to alternately feed and withdraw the work with respect to the cutter, and means operatively associated with said carriage to automatically lower the cutter upon each successive withdrawal of the carriage in preparation for the next cut.

5. In a wood cutting machine having a bed, rails carried upon the bed, vertical ways carried upon the bed, a carrier slidable vertically upon said ways, a rotary cutter mounted with said carrier, manually operable means to adjust the vertical distance between the carrier and the bed, means to rotate the cutter, a movable carriage, means to retain the work upon said carriage, means to alternately feed and withdraw the work with respect to the cutter, a ratchet wheel carried with the means to position the carrier, a pawl, a link connected to the pawl, a crank mounted on the carriage and means to engage the crank on each reciprocation to operate the ratchet and lower the cutter upon each successive withdrawal of the carriage in preparation for the next cut.

This specification signed this 31st day of July, A. D. 1925.

CHRISTOPHER STRAUB.
